TREADMILL

Ray T. Townsend, Des Moines, Iowa, assignor to Townsend Engineering Company, Des Moines, Iowa

Filed May 5, 1972, Ser. No. 50,842

Term of patent 14 years

Int. Cl. D21—02
U.S. Cl. D34—5 K

Fig. 9.

Fig. 10.

FIG. 1 is a top front perspective view of a treadmill showing my new design;

FIG. 2 is a rear elevational view thereof;

FIG. 3 is a right side elevational view thereof;

FIG. 4 is a top plan view thereof;

FIG. 5 is a front elevational view thereof;

FIG. 6 is a top front perspective view of another embodiment of the FIG. 1 design wherein a support bar has been provided thereto;

FIG. 7 is a rear elevational view of FIG. 6;

FIG. 8 is a top plan view of FIG. 6;

FIG. 9 is a front elevational view of FIG. 6; and

FIG. 10 is a right side elevational view of FIG. 6.

The drawing figures are diagonally lined to indicate shiny surfaces.

I claim:

The ornamental design for a treadmill, substantially as shown and described.
